UNITED STATES PATENT OFFICE

2,131,823

LIGHTING FIXTURE

Louis Silberman, New York, N. Y.

Application June 13, 1936, Serial No. 84,984

7 Claims. (Cl. 240—73)

This invention relates to lighting fixtures and is particularly directed to a lighting fixture suspended from a ceiling, and the like articles.

An object of this invention is to provide a lighting fixture of the character described, provided with highly improved means to reflect light upwardly toward the ceiling, the fixture being so constructed that substantially no shadows are cast on the ceiling while producing a soft substantially uniform light throughout the room.

A further object of this invention is to provide in a lighting fixture of the character described, highly improved means for reflecting light downwardly, as well as upwardly toward the ceiling.

A still further object of this invention is to provide a neat and durable lighting fixture of the character described, which shall be comparatively inexpensive to manufacture, easy to assemble, attractive in appearance, and which shall yet be practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention—

Fig. 1 is an elevational cross-sectional view of a lighting fixture embodying the invention suspended from the ceiling;

Fig. 2 is a bottom plan view of an improved lighting fixture;

Fig. 3 is a cross-sectional view taken on line 3—3 of Fig. 1;

Fig. 4 is an enlarged elevational cross-sectional view of a portion of my improved lighting fixture; and

Fig. 5 is a partial enlarged cross-sectional view of the central portion of the fixture.

Referring now in detail to the drawing, 10 designates a lighting fixture embodying the invention suspended from the ceiling 11. The fixture 10 comprises a cylindrical member 12 made of sheet metal, preferably polished or chromium plated on the outer surface. The member 12 may 15 be made of a single elongated strip of sheet metal bent into cylindrical shape with the meeting ends soldered together. Received on the upper edge of the member 12 is an annular bead 13 having a peripheral radial groove 14 on the underside 20 thereof into which the upper edge 12a of the cylindrical member 12 is frictionally received. The bead 13 may be made from an elongated piece of round wire stock grooved longitudinally, fitted over the edge of the strip of metal of which 25 the member 12 is made and then bent with said

strip into circular shape, the member 13 thereafter being soldered to the member 12 for fixing the former to the latter. Soldered or otherwise fixed to the inner surface of the member 12, adjacent the lower edge thereof, is an annular member 15 of angular cross-section having an inwardly extending flange 16.

Mounted on the flange 16 is a circular plate or disc 17 of glass, mirrored on its undersurface 17a to reflect light upwardly. The plate 17 has a central opening 18 for the purpose hereinafter appearing. Contacting the underside of the flange 16 and disposed beneath the plate 17 is a plate 20 of glass preferably mirrored on its upper surface 20a to reflect light downwardly, and to cover the undersurface of the upper plate. The plate 20 is clamped to the plate 17 in the manner to be explained hereinafter, and is preferably made of colored glass to produce highly attractive visual effects. The said plate 20 is likewise formed with a central opening 21 registering with the opening 18. An apertured washer 22, having substantially the thickness of the flange 16, is interposed between the plates 17 and 20, the opening of said washer registering with the openings 18 and 21 of the plates 17 and 20.

Means is provided to clamp the plates 17 and 20 together. To this end, there is provided a member 23 having a substantially spherical portion 24 provided with a downwardly extending stem 25 passing through the openings 18 and 21. At the upper end thereof, the stem 25 has a shoulder 26 contacting the top of the plate 17. The lower end of the stem 25 is screw-threaded to receive a nut 28 screwed thereon for pressing a washer 30 received on said stem against the lower surface of the plate 20.

The spherical portion 24 of the member 23 is furthermore formed with a plurality of horizontal equi-angularly spaced threaded openings 32, into which are screwed lamp sockets 33 extending in radial direction. Lamps 34 may be screwed to the sockets 33. Although three sockets for the reception of three lamps are shown in the drawing, it will be understood that any suitable number of sockets may be provided. The member 23 also has at the top thereof, a vertical screw-threaded opening 35 and an annular shoulder 36 surrounding said opening. Screwed within the opening 35 is a pipe 37, the upper end of which passes through the ceiling for connection to a junction box 38. Surrounding the pipe 37 is a tube 39 resting on the shoulder 36 and preferably polished on its outer surface. A cup-shaped member 40 is received on the tube 39 and fixed thereto by a screw 41, the upper edge of the cup being in contact with the ceiling. The wiring from the junction box 38 passes through the pipe 37 and the member 23 to the sockets 33.

The lamps 34, as shown in the drawing, are 60

located directly above the mirrored plate 17 and within the cylindrical member 12. The light from said lamps are reflected upwardly by the mirror 17 to the ceiling. It will be noted that 5 the only connection between the plate 17 and the ceiling, is at the center of the plate, hence eliminating shadows usually caused by connecting members disposed above the lamps, as in lighting fixtures now in use. The plate 17, being 10 flat, reflects the light upwardly without any substantial loss over a wide area on the ceiling. The colored mirror 20 reflecting light downwardly enhances the lighting effects produced by the lighting fixture. I have found that with 15 my improved lighting fixture a particularly soft and pleasant light is produced for illuminating a room.

The plates 17 and 20 may be removed or replaced readily by merely unscrewing the nut 20 which permits the stem 25 to be lifted out of the openings 18 and 21. Should either of these plates break, replacing is greatly facilitated by reason of the engagement of said plates with opposite sides of the flange 16.

25 The mirror plate 20 reflects downwardly all the light rays impinging thereon. When the lamp 10 is illuminated, the light is reflected upwardly by the mirror 17. The rays of light are reflected to the various walls, the floor and furniture within the room which in turn reflect light to the plate 20 and said plate reflects said reflected light downwardly. There are no direct rays from the lamps 34 to the plate 20, but the light is reflected around the room and finally reaches 30 the plate 20. Furthermore the plate 20 serves to cover the undersurface of the mirror plate 17.

It will thus be seen that there is provided a device in which the several objects of this invention are achieved, and which is well adapted 40 to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new my desire to secure by Letters Patent:

50 1. A lighting fixture comprising a cylindrical member provided with an inwardly extending radial flange, a pair of glass disc reflectors contacting opposite sides of said flange, said discs being formed with registering central openings, a member having a threaded stem extending through said openings, a nut screwed to said stem for clamping said discs together, lamp sockets on said member and lamps in said sockets.

60 2. A lighting fixture comprising a cylindrical member made of sheet metal, an annular bead having a groove receiving the upper edge of said cylindrical member, an annular member of angle-shaped cross-section, fixed to the inner surface of said cylindrical member, adjacent the lower edge of the latter, and having an inwardly extending flange, a pair of glass disc reflectors contacting opposite sides of said flange, means for clamping said plates together at the center, and lamps supported by said means above 65 said discs.

70 3. A lighting fixture comprising a cylindrical

member made of sheet metal, an annular bead having a groove receiving the upper edge of said cylindrical member, an annular member of angle-shaped cross-section, fixed to the inner surface of said cylindrical member, adjacent the lower edge of the latter, and having an inwardly extending flange, a pair of glass disc reflectors contacting opposite sides of said flange, means for clamping said plates together at the center, said means comprising a member having a threaded stem extending through registering openings in said discs, a nut on said stem, and lamps on said stem above said reflectors.

4. A lighting fixture comprising a cylindrical member made of sheet metal, an annular bead having a groove receiving the upper edge of said cylindrical member, an annular member of angle-shaped cross-section, fixed to the inner surface of said cylindrical member, adjacent the lower edge of the latter, and having an inwardly extending flange, a pair of glass disc reflectors contacting opposite sides of said flange, means for clamping said plates together at the center, the adjacent surfaces of said discs being mirrored to reflect light in opposite directions, and lamps supported by said clamping means above said reflectors.

5. A lighting fixture comprising a cylindrical member made of sheet metal, an annular bead having a groove receiving the upper edge of said cylindrical member, an annular member of angle-shaped cross-section, fixed to the inner surface of said cylindrical member, adjacent the lower edge of the latter, and having an inwardly extending flange, a pair of glass discs contacting opposite sides of said flange, and means for clamping said plates together at the center, one of said discs being colored and the other of said discs being mirrored.

6. A lighting fixture comprising a cylindrical member made of sheet metal, an annular bead on said member comprising a wire having a radial groove receiving the upper edge of said member, an annular member of angular cross-section fixed to the inner surface of said first member, and having an inwardly extending flange, a pair of disc reflectors within said first member and on opposite sides of said flange, said discs having registering central openings, a member having a threaded stem extending through said openings, a nut on said stem, lamp sockets on said member, lamps in said sockets, a pipe screwed to said member, and a tube surrounding said pipe.

7. A lighting fixture comprising a cylindrical member made of sheet metal, an annular bead on said member comprising a wire having a radial groove receiving the upper edge of said member, an annular member of angular cross-section fixed to the inner surface of said first member, and having an inwardly extending flange, a pair of discs within said first member and on opposite sides of said flange, said discs having registering central openings, a member having a threaded stem extending through said openings, a nut on said stem, lamp sockets on said last mentioned member, a pipe screwed to said member, and a tube surrounding said pipe, one of said discs being a flat mirrored glass plate and the other of said discs being colored glass.

LOUIS SILBERMAN.
